UNITED STATES PATENT OFFICE.

SIGFRID A. MILLER, OF OAKLAND, CALIFORNIA.

COMBINATION AUTO BED AND TENT.

Application filed October 19, 1920. Serial No. 418,041.

To all whom it may concern:

Be it known that I, SIGFRID A. MILLER, a citizen of the United States, residing at Oakland, in the county of Alameda and State of California, have invented new and useful Improvements in Combination Auto Beds and Tents, of which the following is a specification.

This invention relates to a combination 10 auto bed and tent.

One of the objects of the present invention is to provide a simple substantial campers' combination bed and tent which is so constructed that it may be folded and assembled 15 as a unit of such proportions that it may be readily carried on the running board of an automobile or the like, and when required may be easily and quickly assembled and erected for use.

20 Another object of the invention is to provide a mattress frame of novel construction which is foldable, and which is provided with legs and braces for its support when extended; further to provide a tent frame 25 supported by the mattress frame and detachable with relation thereto, thus permitting the bed to be enclosed or not as desired.

Further objects will hereinafter appear.

The invention consists of the parts and the 30 construction, combination and arrangement of parts as hereinafter more fully described and claimed, having reference to the accompanying drawings, in which—

Fig. 1 is a perspective view of the bed and 35 tent frame showing the parts assembled and erected.

Fig. 2 is an enlarged detail sectional view 40 of one of the supporting legs and the method of securing one of the tent frame poles there-

Fig. 3 is an enlarged detail perspective view showing the connection formed between the side sections and the end sections of the bed frame.

45 Referring to the drawings in detail, A indicates in general a mattress frame which frame consists of a pair of side sections 2 and a pair of end sections 3. The side sections each consists of two members which are 50 pivotally connected as at 4, one side section overlaps the other, one being slotted as at 5 and the other provided with pins 6. The sections of the side rails 2 when extended will thus overlap each other and are interconnected 55 and braced by forming the slots 5 and by

providing the pins 6. The end sections 3 are constructed substantially as shown and they are connected with the side sections or rails 2 by pins 7 and 8; the pin 7 entering a slot 9 formed in the end section, while the 60 pin 8 enters a slot 10 formed in the side rail.

The connection between the side rails and the end sections is thus reinforced and rigidly supported when in place. Both the end sections and the side rails 2 are preferably 65 constructed of angle iron and so are the supporting legs generally indicated at 11. These legs are pivotally attached as at 12 to the end sections and are foldable with relation thereto; the supporting legs having a length 70 approximately one-half the width of the bed. They may thus be folded up in under the end sections and lie parallel therewith when the bed is folded. The legs when extended are secured against accidental folding 75 by braces 13 and 14; the brace 14 being pivotally secured to the legs and having a hook-shaped end 15 which engages a pin on the end section. The brace 13 is pivotally attached to the side rail and its opposite end 80 is hook-shaped and engages a pin 16 secured on the leg 11, that is, each leg is similarly supported and braced so that the description of one will cover the several supporting legs 85 shown.

The bed is particularly designed for campers' use and is so constructed that when it is folded a comparatively small and compact bundle will be formed, which may be readily placed on the running board of an 90 automobile or the like. It is essential that a bed of this character may be quickly and readily assembled, and it is also more or less essential that means be provided for enclosing the same. This feature has been taken care of by providing a detachable tent frame. This frame consists of a pair of upright poles 17, which are inserted through holes 18 formed in one end of the end sections 3. The tent frame further consists of a pair of 100 angularly disposed poles 19, insertable in holes 20, and a pair of longitudinally extended ridge poles 21 and 22. The longitudinally extended poles 21 and 22 are made in two sections to permit reduction of the 105 length of the same when the bed is folded; these sections being connected by securing a sleeve 23 on one section, into which the opposite section may be inserted; the angularly disposed poles being similarly 110

constructed as indicated at 24 to permit shortening of the same for the purpose specified.

The bed when erected with the tent frame 5 in place may be enclosed in any suitable manner or as here shown by a canvas 25; this canvas being secured by placing the legs 11 on one end of the canvas and by driving pegs through eyelets formed in the opposite 10 end.

The angular disposition of the poles 19 is important as it forms an enclosure or space on one side of the bed for the reception of clothing and various articles included in a 15 camping outfit, for instance during rainy weather or the like, and it furthermore provides space when dressing or undressing.

By referring to Fig. 2, it will be seen that the angular poles 19 are provided with tubular pins 25 at their lower ends, which are inserted in the holes 20 formed in the end sections of the bed frame, and it will further be seen that a bracket member 26 is secured to the supporting legs and that a 25 pin-like extension 27 is formed thereon. This pin enters the tubular member 25 forming a guide and a brace for the same, and it furthermore forms a lock which further secures the legs 11 when extended. 30 A similar connection is formed between the uprights 17 on the outermost legs of the bed frame.

In actual operation if it is desired to fold the bed, it is first necessary to remove the 35 canvas covering; secondly the ridge poles 21 and 22; third, the uprights 17 and 19. With these parts removed it will be seen that the bed frame proper remains. This is folded by first releasing the braces 13 and 40 14 and folding them parallel with the parts to which they are attached. The side rails are next engaged by their center portions and lifted in an upward direction. This breaks the joint or pivotal connection 4 of 45 the side rails and takes the strain or pull off the spring mattress generally indicated at B. The side rails may now be disconnected with relation to the end sections 3 and folded, and the supporting legs 11 are 50 then folded under the end sections. The several disconnected parts may now be assembled in a bundle and the bedding, together with the uprights and ridge poles of the tent frame rolled into the canvas cov-

55 ering. The entire unit thus forms a compact bundle which may be readily handled and placed wherever convenient, for instance on the running board or on the rear end of an automobile or otherwise. When 60 erecting the bed and tent when it is required, the operation is reverse to that just described.

Some of the important features to be considered in the present instance are, first the 65 fact that a bed has been provided which

may be readily assembled or folded as desired; secondly a comparatively simple tent frame is provided which may be employed or not as occasions may demand; third a spring mattress is provided which exerts 70 such a pull that accidental disconnection of the side rails with relation to the end sections 3 cannot occur, thus permitting the use of a comparatively simple connection between the same; fourth, rigid braces are 75 employed for securing the supporting legs when in extended position, and these braces are further reinforced if the tent frame is employed as the uprights of the tent frame form an interlock with the legs as shown in 80 Fig. 2.

The entire structure may be constructed of comparatively light material, and while the description supplied has specified more or less limited detail features, I wish it understood that various changes in form and proportion may be resorted to within the scope of the appended claims, similarly that the materials and finish of the several parts employed may be such as the experience and 85 judgment of the manufacturer may dictate or varying uses may demand.

Having thus described my invention, what I claim and desire to secure by Letters Patent is—

1. In a device of the character described a bed frame, an end section in said bed frame, a pair of supporting legs pivotally attached thereto, said legs adapted to fold inwardly against the end section, a pair of 100 brace links attached one to each leg, a hook shaped end on each brace member, a pair of pins secured to the end frame section with which said hook shaped members are adapted to engage and secure the legs in extended 105 position, a hole formed in each end of the end frame section, a tubular member insertable in each hole, and a pin on each leg adapted to be received by the tubular members.

2. In a bed of the character described the combination with the main frame and the supporting legs pivotally attached thereto, of a pair of upright members adapted to be supported by the bed frame one at each 115 end thereof, said upright members extending through the main frame and having their lower ends disposed in substantial parallelism with the pivotally mounted legs when these are vertically disposed, and a locking connection between each upright member and the adjacent pivoted leg, said locking connections securing the legs against 120 pivotal movement when the uprights are in place, said locking means also limiting 125 downward movement of the upright members with relation to the main frame and the legs.

3. In a bed of the character described the combination with the main frame and the 130

- pivottally attached legs supporting the same, of a pair of upright members adapted to be supported by the frame one at each end thereof, a tubular member on the lower end 5 of each upright, a perforation formed in each end of the frame for the reception of said tubular members, and a pin on each adjacent supporting leg adapted to be received by the tubular members.
- 10 4. A bed of the character described comprising side bars, end bars bent at each end to overlap the contiguous ends of the side bars, supporting legs pivotally connected to the end bars, a bracket secured to each of said legs, said brackets having an upwardly turned extension, and upright members having tubular lower ends adapted to extend through the end rails and engage the extensions on the brackets so as to support the upright member and secure the said 15 legs against pivotal movement.

SIGFRID A. MILLER.
